BOTTLE

Curt Johnny Lind, Alvsjo, Sweden, assignor to Molnlycke
Aktiebolag Krokslatt, Goteborg, Sweden

Filed Apr. 3, 1969, Ser. No. 16,566

Claims priority, application Denmark Oct. 3, 1968

Term of patent 7 years

Int. Cl. D9—01

U.S. Cl. D9—2

FIG. 1 is a top plan view of a bottle embodying my new design;

FIG. 2 is a side elevational view of said bottle;

FIG. 3 is a bottom plan view of said bottle;

FIG. 4 is a front elevational view of said bottle, and

FIG. 5 is a rear elevational view thereof.

I claim:

The ornamental design for a bottle, substantially as shown.
